CLAIM

The ornamental design for a medical liquid applicator with crescent shaped convex part, as shown and described.

DESCRIPTION

FIG. 1 is a front view of a medical liquid applicator with crescent shaped convex part, with an application pad attached, the rear view being a mirror image thereof; FIG. 2 is a plan view thereof, including the attached application pad;

FIG. 3 is a bottom view thereof, again including the attached application pad;

FIG. 4 is a bottom view of the medical liquid applicator with crescent shaped convex part, without the application pad;

FIG. 5 is an enlarged view of the portion within the dash-dot-dash circle 5 of FIG. 4, again without the application pad;

FIG. 6 is a cross-sectional view taken along line 6-6 of FIG. 5;

FIG. 7 is a right side view thereof, with the application pad; and,

FIG. 8 is a left side view thereof, again with the attached application pad.

The broken lines shown in FIGS. 1-8 illustrate portions of the medical liquid applicator with crescent shaped convex part form no part of the claimed design.

The dash dot lines shown in FIGS. 4 and 5 illustrate areas where an enlarged section is taken and as cross-section indicators that form no part of the claimed design.

The present article is intended for use as a medical liquid applicator.
